IMPREGNATING PAPER FOR INSULATION OF ELECTRIC CABLES AND APPARATUS THEREFOR

Application filed March 16, 1929, Serial No. 347,700, and in Great Britain March 7, 1928.

This invention has reference to the impregnating of paper for the insulation of electric cables.

In the impregnating of paper for the purpose aforesaid it is of the highest importance to extract so far as possible all the air and moisture from the body of the paper.

Heretofore it has been the practice to conduct the paper from a drum into a tank containing liquid compound with which it is to be saturated, round rollers in such tank, and eventually out of the tank and on to another drum on which it is wound, passing scrapers and such like devices on its journey to the last drum, and in some cases the paper is carried over hot rollers before being immersed in the compound with the object of causing air in the crevices thereof to expand and dissipate before the paper enters the compound.

According to this invention the whole of the process of saturating is carried out in a vacuum, thus assisting in the setting free of all air from the body of the paper.

For this purpose we construct apparatus comprising a lidded tank, the joints being capable of being made air tight, adapted to contain molten compound, into and through which the paper travels while being drawn off of a drum, and rewound on another drum, with means whereby the paper is subjected to the effect of the vacuum before being immersed in the compound and preferably also while being so subjected is carried over hot rollers.

An example of apparatus made in accordance with this invention is illustrated in the accompanying drawings. Fig. 1 is a side view of the apparatus. Fig. 2 a front view looking in the direction of the arrow shown to the left of Fig. 1. Fig. 3 is a plan view. Figures 4 and 5 are respectively a vertical section and a plan view of the supplemental tank and seating device, described on an enlarged scale and Fig. 6 a vertical section of a part on an enlarged scale.

a is an air-tight chamber with an extension *a*¹. The extension *a*¹ has a rectangular aperture or opening on the top for the purpose of introducing the drum of paper to be insulated and such aperture is provided with a

cover or lid *a*² adapted to hermetically seal the hole. The main part of the tank has an elongated aperture at the top provided with a cover *a*³ adapted to hermetically seal such aperture. A metal frame *a*⁴ on which are mounted three rollers *a*⁵ being guides for the paper as it travels through the liquid insulating material. The frame *a*⁴ is so arranged that on removing the cover the frame and rollers can be withdrawn from the tank for the purpose of manipulating the paper, and from the sides of the tank webs are projected to guide the frame to its correct position. *a*⁶ are doors to an opening in the front of the main part of the tank also adapted when closed to hermetically seal the opening. *a*⁷ is a wall extending right across the main tank and from the bottom to near the top as illustrated. *a*⁸ are rollers to guide the paper up and down the chamber before being immersed in the insulating material. *a*⁹ is an elongated slot in the roof of the tank *a*, through which the paper issues, *a*¹⁰ are three guide rollers, *a*¹¹ are steam pipes for heating the rollers *a*⁸, and *a*¹² is an orifice adapted for the attachment of the vacuum pump. *b* is a narrow elongated tank open to the atmosphere, *b*¹ are flat oblong rubber blocks held in position, by holders *b*². The positions of the rubber blocks are adjustable by the threaded rods *b*³ located in the brackets *b*⁴ and engaging respectively the blocks *b*⁵ which are secured to the holders *b*². *c* is a trough with a roller *c*¹ and pulley *c*² mounted on the same shaft. *d* is the winding up drum driven by gear wheel *d*¹. *e* is a hollow pull off wheel driven by gear wheel *e*¹ cooled by a flow of cold water through its interior, and *e*² is a driving pulley on the same shaft for the purpose of driving the roller *c*¹ through the pulley *c*². *f* are scraping knives, each connected to a steam pipe for the purpose of being kept hot. *g* are steam pipes through which steam is continuously passed in order to keep the liquid in the tank *a* and in the trough *c* and also the scraping knives *f* at the required temperature. *h* is a pump driven by the pulley *h*¹ and which is driven by band *h*², adapted to pump liquid from the tank *a* via the pipe *h*³ into the tank *b*. *h*⁴ is an over-flow pipe carrying liquid from

the tank *b* into a chamber *h*⁵ from which it can pass from time to time by the opening of the valve *h*⁶ in the tank *a*. *i* is a pump adapted to extract air from the inside of the tank *a*. *j* is a drum carrying the paper to be impregnated.

The apparatus is driven through the pulley *k* on the shaft of which is the gear wheel *k*¹ in mesh with the gear wheel *d*¹ through which the receiving mandrel *d* is driven.

10 The shaft *d*⁵ and the mandrel *d* are rotatably connected by means of a readily detachable coupling *d*⁴.

15 The gear wheel *d*¹ is frictionally mounted on the shaft *d*⁵ so as to accommodate the increase of diameter as the paper is wound up on the mandrel *d*.

20 The chain *d*² on the sprocket *d*³ mounted on the shaft *d*⁵ drives the chain wheel *e*¹, and 20 the band on the pulley *e*² drives the pulley *c*².

25 The part of the machine comprising the paper after it leaves the tank *b*, the haul off wheel, and the receiving mandrel are all enclosed in a suitable room or chamber *m* grammatically shown in Fig. 1 kept in a suitable atmosphere and at the required temperature for the purposes of preventing the re-absorption of atmospheric moisture. The parts 30 designated *n*¹, *n*², *n*³, *n*⁴, are gated openings in the walls of chamber *m*.

The apparatus is worked and functions as follows:—

35 By opening the doors and lids the drum *j* can be mounted on bearings, the paper placed around the guides *a*¹⁰ and rollers *a*⁸ and *a*⁵ and through the slot *a*⁹ past the scraping knives *g* over the roller *c*¹ around the haul off roller *e* and on to the receiving mandrel *d* all as indicated by the arrows. It will be realized that when the lid *a*⁸ is open the frames *a*⁴ and the rollers *a*⁵ are easily accessible.

40 The rubber blocks on either side of the slot *a*⁹ are closed up to the paper and fixed in position, the doors and lids are then closed down to render the inside of the tank hermetically sealed, the heating steam is turned on, the pump worked to extract the air from inside the chamber *a*, the pump *h* started to work, and the valve *h*⁶ of the chamber *h*⁵ set to 50 maintain a predetermined heat of liquid above it.

45 The tank *a* when the paper is in position is filled on the right side of the wall *a*⁷ up to the level indicated by the dotted line with 55 the impregnating fluid material and a quantity of the like fluid material is poured into the tank *b*.

50 The trough *c* is filled with a suitable material for the purpose of providing a surface coating of non-adhesive character on one side of the paper sheet. The driving is then started.

55 It will be obvious that a quantity of the impregnating liquid will leak past the paper or fabric issuing from the slot *a*⁹, from the

tank *b* into the tank *a*. This will be constantly rectified by the pump *h* which is re-delivering liquid from the tank *a* into the tank *b* and in case of any over-flow from the tank *b* the liquid will be re-delivered to the tank *a* 70 through the pipe *h*⁴ and the valve *h*⁶.

What I claim is:—

Apparatus for the purpose of impregnating a long strip of fibrous material with electrically insulated material, comprising a tank 75 adapted to contain the impregnating material in a liquid form and to be hermetically sealed; means for producing and maintaining a vacuum in such tank, a slot being formed in the exit end of such a tank adapted for 80 passing a strip of material out of the tank, a supplemental tank disposed above said first mentioned tank and communicating therewith through said slot and adapted to contain a quantity of the insulating material, a 85 pump adapted to pump liquid from the main tank into the supplemental tank, an overflow from the supplemental tank discharging through an adjustable valve into the main tank and means for drawing the paper from a drum through the said liquid and out of the main tank via the slot and supplemental tank.

In testimony whereof I have hereunto affixed my signature.

CHARLES JAMES BEAVER.
